DESIGN FOR A HAND MONOCULAR VIEWER

Charles E. Kidner, Old Greenwich, Conn.

Application January 5, 1945, Serial No. 117,269

Term of patent 7 years

(Cl. D57—1)

To all whom it may concern:

Be it known that I, Charles E. Kidner, citizen of the United States and resident of the city of Old Greenwich and the State of Connecticut, county of Fairfield, have invented a new, original, and ornamental Design for a Hand Monocular Viewer, of which the following is a specification, reference being had to the accompanying drawing, forming a part thereof.

Fig. 1 is a rear elevation of a hand monocular viewer embodying my design.

Fig. 2 is a side elevation thereof.

Fig. 3 is a front elevation thereof.

I claim:

The ornamental design for a hand monocular viewer, substantially as shown.

CHARLES E. KIDNER.
